UNITED STATES PATENT OFFICE.

CHRISTIAN LOETSCHER, OF DUBUQUE, IOWA.

MORTISING-MACHINE.

SPECIFICATION forming part of Letters Patent No. 495,350, dated April 11, 1893.

Application filed April 23, 1892. Serial No. 430,362. (No model.)

To all whom it may concern:

Be it known that I, CHRISTIAN LOETSCHER, of Dubuque, in the county of Dubuque and State of Iowa, have invented a new and Improved Mortising-Machine, of which the following is a full, clear, and exact description.

My invention is an improvement in the class of chain tool mortising machines.

The invention consists of certain parts and details and combinations of the same, as will be hereinafter described and then pointed out in the claims.

Reference is to be had to the accompanying drawings forming a part of this specification, in which similar letters of reference indicate corresponding parts in all the figures.

Figure 1 is a front elevation of the improvement. Fig. 2 is a side elevation of the same. Fig. 3 is a sectional side elevation of the same on the line 3—3 of Fig. 1. Fig. 4 is an enlarged front view of the adjustable blocks for controlling the clamping device, with parts in section; and Fig. 5 is a side elevation of one of the said blocks.

The improved mortising machine is mounted on a suitable column A, from the rear end of which extends a frame A', carrying the shafting hereinafter more fully described. On the front of the column A are arranged the vertical guide-ways A², on the lower part of which is fitted to slide the bed plate frame B, formed at its front with a semi-circular recess B', into which fits a correspondingly-shaped tilting frame C, adapted to be clamped to the bed frame by bolts C', held in the said bed frame, and passing through slots in the said tilting frame C. From the latter extend forwardly guideways C², in which is fitted to slide transversely the bed plate D, adapted to support the article to be mortised.

The transverse adjustment of the bed plate D is accomplished by the usual screw E screwing in the tilting frame C and turning loosely in a projection on the front end of the said bed plate D, the outer end of the screw being provided with a suitable handle E' for turning the screw to move the bed plate D in or out on the guideways C². In the top of the bed plate D is formed a transversely-extending recess in which is fitted to slide a clamping plate F, for locking the material to be

mortised in place on the bed plate D, the back of the material resting on a vertically-arranged gage G, supported on the bed-plate D, as hereinafter more fully described.

On a lug of the clamping plate F screws a bolt F', carrying on its inner end a plate F², abutting against the front side of the material under treatment. By adjusting the screw F', the plate F² can be moved in or out so as to bring the said plate in proper position relative to the thickness of the material under treatment. The gage G extends longitudinally as plainly illustrated in the drawings, and is formed with downwardly-extending slotted arms G', engaged by bolts G², screwing in the bed plate D and serving to hold the said gage in proper position, at the same permitting its vertical adjustment according to the size of the material under treatment.

On the top of the gage G is arranged a transversely-adjustable plate G³, adapted to engage the top of the material so that the latter is securely held in place on the bed plate by the back of the gage G, the top G³, the plate F² and the clamping plate F. From the rear end of the clamping plate F extends transversely, a rod H, the axis of which forms the center for the semi-circular recess B' in the bed plate frame B, so that when the tilting frame C is tilted it swings from the axis of the rod H. On the latter is secured a collar H', pressed on by a flat spring H², secured to the bed plate frame B. A second collar H³, is arranged on the end of the rod H, as will be readily seen by reference to Fig. 3, and this collar is engaged by the fork end of an arm H⁴, pivoted on the bed plate frame B. The pivoted arm H⁴ is curved rearwardly and carries at its lower rear end a friction roller H⁵, adapted to travel over a series of blocks I, I', I², I³, arranged alongside each other and resting with their backs on the column A. The blocks I', I² and I³ are formed on their inner sides with pins I⁴, engaging corresponding grooves I⁵, arranged vertically in the sides of the adjacent blocks I, I', I² respectively, as will be readily understood by reference to Figs. 4 and 5.

The two outermost blocks I and I³ are provided with upwardly-extending rods I⁶ fitted to slide in suitable bearings formed in the

55

upper part of the column A. Screws I⁷ screwing in the said column at the sides thereof, serve to lock the said rods in place after the latter have been adjusted vertically to bring 5 the several blocks I, I', I² and I³ into the proper position according to the mortise to be cut into the material as hereinafter more fully described. The friction roller H⁵ on the pivoted arm H⁴ is adapted to travel up the two 10 inclines I⁸ and I⁹ formed on the lower and upper parts of each of the blocks.

When the bed plate frame B rises the friction roller H⁵ travels over the inclines I⁸ of the several blocks, thus imparting a swinging 15 motion to the arm H⁴ so that the upper forked end moves rearward and pulls on the collar H³ so as to move the rod H and the clamping plate F in a like direction, whereby the plate F² is moved in contact with the front side of 20 the material under treatment, and the said material is pressed against the gage H and securely clamped thereon.

When the friction roller H⁵ travels down either of the inclines I⁸ or I⁹, then the spring 25 H² pressing on the collar H' causes a forward sliding of the rod H and the plate F so that the plate F² is moved out of contact with the front side of the material. Thus, it will be seen that by the forward and downward movement 30 of the bed plate frame B, the material is automatically clamped in position on the bed plate B and the gage G or automatically released as above described. The material is mortised by the usual chain tool J arranged above the bed 35 plate B and passing at its lower end over the sprocket wheel J' journaled in the lower end of an arm J² secured to a transversely-extending slide J³ mounted to slide vertically on the guideways A² of the column A above the bed 40 plate frame B. A screw rod J⁴, mounted to turn in the upper part of the column A screws in a nut on the said slide J³ and on the upper end of the said screw rod is secured a handle J⁵ for turning the screw rod so as to 45 raise and lower the slide J³, and consequently the sprocket wheel J', to give more or less tension to the chain tool J. The upper part of the latter passes over the sprocket wheel J⁶, secured on the shaft K, extending trans- 50 versely and mounted to turn in suitable bearings of which one is arranged on the upper end of the column A, and the other on the frame A'.

On the shaft K and directly in the rear of 55 the sprocket wheel J⁶, is secured an exhaust fan wheel L, revolving in a stationary casing L', fastened to the upper end of the column A. The casing L', is provided in its front with an opening L², in close proximity to the 60 upper part of the chain tool J, so that chips, dust, &c., adhering to the chain tool are drawn into the opening L², by the suction blast, to be discharged through the outlet spout L³, arranged in the said casing L'. A curved guard 65 L⁴ is arranged on the front of the casing L', and extends over the top of the chain tool J, the said guard L⁴, being hinged or pivoted on

a downwardly-extending straight guard plate L⁵, attached to the casing and which serves to guide any loose material up into the opening L², to be discharged by the suction fan through the outlet spout L³. It will be seen that by this arrangement, the chain tool J, can be kept very clean so that a proper mortise will always be cut by the tool. By hinging the guard L⁴, access is had to top chain wheel.

On the shaft K is secured a pulley K' over which passes a belt K² also passing over a pulley N' secured on the driving shaft N, 80 mounted to turn in suitable bearings in the lower part of the column A and frame A'. On the outer ends of this shaft N are secured the fast and loose pulleys N² and N³ connected by a belt N⁴ with counter-shafting for imparting a rotary motion to the said driving shaft N which, by the pulley N', the belt K² and the pulley K' imparts a rotary motion to the shaft K and the latter by the sprocket wheel J⁶ causes the chain tool J to travel in the usual 85 manner in order to cut the mortise in the material under treatment. The main driving shaft N also imparts a vertical sliding motion to the bed plate frame B, and the parts supported thereby, as previously described and 90 for this purpose the following device is provided. The bed plate frame B is formed with a nut B² in which screws the feed screw shaft O arranged vertically and mounted to turn in suitable bearings formed on the column A 95 between the two guideways A².

On the upper end of the feed screw shaft O is secured a bevel gear wheel O' in mesh with a bevel gear wheel O² attached to the front end of a transversely-extending shaft O³ 105 mounted to turn in suitable bearings on the column A and frame A'. On this shaft O³ is secured a fast pulley O⁴ on one side of which is arranged a loose pulley O⁵ and a like pulley O⁶ is arranged on the other side of the said fast pulley O⁴, as will be readily understood by 110 reference to Figs. 2 and 3.

A belt P passes over the loose pulley O⁵ and is adapted to be shifted onto the fast pulley O⁴, as hereinafter more fully described, the said 115 belt extending downwardly and passing over a pulley P' held on the shaft N. Over the other loose pulley O⁶ also passes a belt P² adapted to be shifted from the said pulley O⁶ onto the fast pulley O⁴, as hereinafter more fully described, the said belt also passing over a pulley P³ secured on a transversely-extending shaft P⁴ mounted to turn in suitable bearings on the frame A'. On this shaft P⁴ is secured a cone pulley P⁵ over which passes a cross belt P⁶ also passing over a cone pulley P⁷ secured on the driving shaft N. When the machine is not in operation, that is, when the belt N⁴ passes over the loose pulley N³ on the driving shaft N, then the latter is at a standstill and the belts P and P² both engage the loose pulleys O⁵ and O⁶ as plainly shown in 120 Fig. 2. Now, in order to shift the said belts P and P² automatically when the machine is in 125 130

operation, the following device is provided, the said device being actuated from the bed plate frame B. On the latter is secured a rearwardly-extending arm B³ engaging a rod Q mounted to slide vertically on one side of the column A. On this rod Q are secured the collars Q' and Q² located below and above the said arm B³, as will be readily seen by reference to Fig. 2. The collars Q' and Q² can be vertically adjusted on the rod Q and are provided for this purpose with the usual set screws. On the upper end of the rod Q presses a spring Q³ supported on the column A and serving to hold the said rod Q in an uppermost position.

On the rod Q above the collar Q² is secured an arm R extending rearwardly and formed at its rear end with a fork engaging one arm of a T-shaped shifting lever S, fulcrumed on the frame A' and arranged to engage both belts P and P² in such a manner that when one belt is moved toward the fast pulley O⁴ the other is moved away therefrom onto its corresponding loose pulley. When the shifting lever S is in a normal position as illustrated in Fig. 2, both belts P and P² are on their loose pulleys and consequently no rotary motion is given to the shaft O³ which actuates the feed screw shaft O. The lower end of the rod Q is pivotally connected with the free end of an arm Q⁴ extending longitudinally in the lower part of the column A and pivoted thereto, as illustrated in Fig. 1. This arm Q⁴ is adapted to be engaged on top by a foot lever T extending transversely and fulcrumed at its rear end on the frame A'.

From the fulcrumed end of the foot lever T, extends upwardly an arm T' pivotally connected by a link T² with one end of a shifting rod U mounted to slide transversely in suitable bearings on the frame A', the said shifting rod being provided at its rear end with two shifting arms U' engaging opposite edges of the belt N⁴. A spring U² is coiled on this shifting rod U for holding the same in an outermost position as shown in Fig. 2, the said spring also serving to hold the foot lever T in an uppermost position as the latter is connected with the said rod U in the manner described.

The operation is as follows: When the several parts are in the position shown in Figs. 2 and 3, and the operator has placed the material to be mortised onto the bed plate D between the gage G and the arm F² and then presses the foot lever T, then the rod U slides forwardly and shifts the driving belt N⁴ onto the fast pulley N², so that the main driving shaft N is rotated. A rotary motion of the latter is transmitted to the shaft K as above described, whereby the chain tool J is set in motion and at the same time the suction fan L is actuated as above described. A further downward pressing of the lever T brings the latter in contact with the pivoted arm Q⁴ so that the latter is swung downward and by its connection with the rod Q causes the latter

to slide downward, whereby the spring Q³ is pressed and at the same time the arm R held on the said rod Q actuates the double shifting lever S so that the belt P² is shifted from the loose pulley O⁶ onto the fast pulley O⁴. The rotary motion of the main driving shaft N imparted by the cone pulleys P⁷, P⁵ and the cross belt P⁶ to the shaft P⁴ now causes a rotary motion of the shaft O³ as the latter is now connected by the fast pulley O⁴, the belt P² and the pulley P³ with the said revolving shaft P⁴. The rotary motion of the shaft O³ is transmitted by the bevel gear 70 wheels O² and O' to the feed screw shaft O, whereby the bed plate frame B is caused to travel upward on its guideways A² as the said feed screw shaft O engages the nut B² on the said bed plate frame B. On the upward 85 movement of the bed plate frame B, the friction roller H⁵ travels up the inclines I⁸ on the blocks I, I', I², I³, whereby the clamping plate F is caused to slide transversely as above described to securely clamp the material in 90 place on the bed plate D. On the further upward movement of the bed plate frame B, the top of the material is brought in contact with the lower cutting end of the chain tool J so that the mortise is cut into the material. On 95 the further upward movement of the bed plate frame B the mortise is cut to the desired depth or entirely through the material, as the case may be, the clamping plate F, as well as the bed plate D being provided with longitudinal slots for the passage of the lower end of the tool so as to prevent the latter from coming in contact with any metal on the bed plate and at the time it cuts through the bottom of the material under treatment. 100 The collars Q' and Q² have been set on the rod Q according to the depth of the mortise to be cut, so that on the further rising of the bed plate frame B, the arm B³ finally comes in contact with the collar Q² at the time the 105 desired depth of the cut is reached. The arm B³, in moving against the collar Q² raises the rod Q whereby the arm R actuates the double shifting lever S so that the belt P² is moved from the fixed pulley O⁴ onto the loose pulley 110 O⁶ and at the same time the other belt P is moved from its loose pulley O⁵ onto the fast pulley O⁴, whereby the motion of the shaft O³ is reversed and the feed screw O is caused to travel in an opposite direction thereby imparting a downward sliding motion to the bed plate 115 frame B and parts supported thereon. It is understood that the shaft O³ is reversed as above described owing to the reverse motion given to the shaft P⁴ by the cross belt P⁶ connecting the main driving shaft N with the shaft P⁴. When the bed plate frame B moves downward as above described, the chain tool J is finally withdrawn from the cut made by it in the material and at this time the friction roller H⁵ of the arm H⁴ travels down the incline I⁸ on the blocks I, I', &c., so that the spring H² causes a forward sliding of the clamping plate F whereby the plate F² is 120 125 130

5 moved away from the front of the material, and the latter is thus released, and can be removed from the bed plate for the insertion of another piece of material to be mortised or 10 the said material can be shifted on the bed plate for a new cut. At this time, the bed plate frame B by its arm B³ engages the collar Q' so that the rod Q is moved downward and the double shifting lever S is again actuated and by it the belt P is moved from the fast pulley O⁴ onto the loose pulley O⁵ and at the same time the other belt P² is moved from the loose pulley O⁶ back onto the fast pulley O⁴, whereby a rotary motion is given 15 to the shaft O³ in an opposite direction from the one it previously had, so that the feed screw O revolves in an opposite direction and again feeds the bed plate frame B upward on the guideways A² and the above described operation is repeated.

20 It will be seen that by this machine, after it has once started no further attention is required so far as the working parts are concerned, as the several mechanisms are actuated automatically and the operator only removes the material to be treated or shifts the same on the bed plate D, so as to bring the material in the proper position for the tool to mortise the same at the proper spot.

25 Having thus fully described my invention, I claim as new and desire to secure by Letters Patent—

30 1. The combination, with the work-table, adapted to reciprocate vertically, of a clamping plate sliding transversely on said table, an arm pivoted to the table, and blocks having inclines and arranged in the path of the said arm and made adjustable, substantially as shown and described, for the purpose specified.

35 2. The combination with a bed plate frame, of a tilting frame mounted to turn on the said bed plate frame, a bed plate held laterally adjustable on the said tilting frame, and a clamping plate fitted to slide on the said bed plate and provided with a rod, the axis of which forms the center of the said tilting frame, substantially as shown and described.

40 3. The combination with a bed plate frame, of a tilting frame mounted to turn on the said bed plate frame, a bed plate held laterally adjustable on the said tilting frame, a clamping plate fitted to slide on the said bed plate and provided with a rod, the axis of which forms the center for the said tilting frame, and a spring for holding the said clamping plate in a normal position, substantially as shown and described.

45 4. The combination with a bed plate frame, of a tilting frame mounted to turn on the

5 said bed plate frame, a bed plate held laterally adjustable on the said tilting frame, a clamping plate fitted to slide on the said bed plate and provided with a rod, the axis of which forms the center for the said tilting frame, an arm pivoted on the said bed plate frame and engaging the said rod, the said arm being adapted to receive a swinging motion on the upward movement of the said bed plate frame, so as to shift the said clamping plate, substantially as shown and described. 65 70

5. The combination with a bed plate frame, of a tilting frame mounted to turn on the said bed plate frame, a bed plate held laterally adjustable on the said tilting frame, a clamping plate fitted to slide on the said bed plate and provided with a rod, the axis of which forms the center for the said tilting frame, an arm pivoted on the said bed plate frame and engaging the said rod, the said arm being adapted to receive a swinging motion on the upward movement of the said bed plate frame, so as to shift the said clamping plate, and blocks having inclines and adapted to be engaged by the free end of the said pivoted arm, substantially as shown and described. 75 80

6. The combination with a bed plate frame mounted to slide vertically, of a feed screw shaft engaging the said bed plate frame, a main driving shaft for imparting a rotary motion to the said feed screw shaft in either direction, and a shifting device, substantially as described, controlled from the said bed plate frame for imparting forward and backward motion to the said feed screw shaft, substantially as shown and described. 90 95

7. The combination with a chain tool and a shaft carrying a sprocket wheel over which passes the said tool, of a rotary fan mounted upon and driven by said shaft, and provided with a hood whose central inlet is behind and in close proximity to the said sprocket wheel and chain, substantially as shown and described. 100

8. The combination with a chain tool and a shaft carrying a sprocket wheel over which passes the said tool, of a suction fan driven from the said shaft and having its inlet in close proximity to the said sprocket wheel and chain tool, and a hood held on the front of the casing of the said suction fan and extending down alongside of and curved over the top part of the said chain tool and over the said sprocket wheel, substantially as shown and described. 105 110
